UNITED STATES PATENT OFFICE.

REGINALD ARTHUR KING, OF LONDON, ENGLAND.

GAME APPARATUS.

1,132,189.

Specification of Letters Patent. Patented Mar. 16, 1915.

Application filed October 3, 1914. Serial No. 864,763.

To all whom it may concern:

Be it known that I, REGINALD ARTHUR KING, a subject of His Majesty the King of England, residing at 188 Frant road, 5 Thornton Heath, London, England, have invented certain new and useful Improvements in Game Apparatus, of which the following is a specification.

This invention relates to apparatus for 10 playing a game of skill with the aid of a ball or the like, and has for its chief object to provide improved means for controlling the movement of the ball or the like so as to urge it toward or away from a goal or 15 other prearranged point. According to this invention, the movement of the ball or the like is controlled by means, hereinafter termed "drivers", which are capable of both reciprocatory and rotary movements 20 whereby the ball or the like can be urged in any desired direction.

In order that this invention may be clearly understood and readily carried into effect, I will proceed to describe the same 25 with reference to the accompanying drawings, which show certain embodiments of the invention, and wherein:—

Figure 1 is a perspective view of one 30 form of the apparatus, showing the position of the ball and drivers as they might appear in play. Fig. 2 is an enlarged broken view in perspective of one of the drivers and its operating means illustrated in Fig. 1; and, Fig. 3 is a view in perspective of one side of a modified form of the 35 apparatus.

Describing the form of apparatus shown 40 in Figs. 1 and 2 of the drawings, A is the game board partly surrounded by guards or rails B which are so constructed as to prevent the ball rolling off the board and also allow for movement of the drivers C over same. The game board is also provided with parallel guides in the form of slots or 45 grooves α extending from end to end thereof. The drivers are intended to work along said guides α , and they may comprise wire or other forks fashioned somewhat after the form of a Y, (shown more clearly in 50 Fig. 2), the outer portions c of the mutually opposite limbs or arms of which are bent inward so as to lie parallel with one another. Projecting from the junction of said limbs or arms with the stem c' , and at right 55 angles to the plane of the Y, is provided a somewhat U-shaped extension, the outer

limb c^2 of which is shorter than the inner limb c^3 and points toward the plane of the Y and which may lie in a plane at right-angles to the plane of the stem of the Y. 60

A pair of rods D, hereinafter termed "operating-rods", adapted to work side by side, is also provided, and such rods are connected together at one end by the U-shaped extension c^2 , c^3 and at the other end 65 by another U-shaped wire or the like E', the limbs of which latter, after passing through the operating rods, are fixed in an operating knob E or the like. The limb c^3 of each driver is entered into one of the 70 slots α of the board and is provided with a washer c' , or other device, which rests on opposite sides of the slot and raises the Y clear of the board. It will be seen that by coupling the drivers C and the knobs E to 75 the operating rods D in the manner described the former can be readily turned in a rotary direction by twisting the knobs.

There may be any desired number of drivers provided and a corresponding number of pairs of operating rods, a convenient arrangement being that shown in Fig. 1 in which there are six drivers arranged to work along a corresponding number of 80 grooves α in the board, three of them being 85 operated from one end of the board and alternating with the remaining three which are operated from the opposite end thereof.

The board is provided with a goal at each 90 end, and when the board has six grooves α , the goals are preferably arranged at the ends of the two middle grooves thereof respectively. The goals are defended by goal-keepers F which are of similar construction to the drivers C (excepting that they have 95 no stems c'), the inner limb f of the V-shaped extension working in a suitable support in the board and the outer limb f' being connected to a rod G adapted to be moved longitudinally in guides g , and provided with an operating handle g' . The farther rod g is not visible in Fig. 1, but its operating handle g' can be seen. 100

The board is provided with downwardly projecting ends a' which serve to raise it 105 from the table or other surface on which it is placed and through which ends the operating rods D work. The limbs c^2 , c^3 of the drivers are continued down below the operating rods, as shown in Fig. 2, so as to 110 engage the downwardly projecting ends a' of the board when the operating rods are

drawn back to their farthest limit and thus prevent their being withdrawn altogether.

Spots a^2 are provided on the board to indicate the positions the drivers should occupy at the commencement of play or upon restarting after a goal has been scored. In playing, the ball H is placed on a spot a^3 in the center of the board and the object of the game is to force it through the opponents' goal, which is done by one of the players suitably manipulating his driver. Immediately the ball commences moving, the opponents operate their drivers, so as to defend their goal and attack the goal of the opposing side, to do which they can move the drivers along the slots and at the same time, if necessary, impart rotary movement to the drivers by turning the operating knobs. The opposing side then acts similarly. The players can either manipulate the drivers so as to receive the ball between the limbs of the Y or strike it with the stem and outer sides of the limbs thereof, and thus urge it in any direction they please. The goal-keepers are operated by moving their rods G backward or forward so as to turn them in the desired direction.

The game may be taken part in by two, three or four players, who sit at each end of the board and control the drivers or strikers by means of the operating knobs, as already explained. When one player controls one of the goal-keepers only, he may sit at the side of the board. In some cases, in accordance with this invention, the goal-keepers F are dispensed with, the goals being left in the form of plain openings, or in the form of raised portions, of the wire guards B, said goals being defended entirely by the players. Also, in carrying out this invention, instead of forming the slots a in the board the latter may be left plain and the operating rods D be guided in suitable guides arranged above the board. Or, as shown in Fig. 3, the operating rods D may be dispensed with, the drivers C being suspended on wire guides j fixed in and arranged above the plain board A and provided with operating handles c^5 by which they can be reciprocated and rotated on the guides j .

What I claim as my invention and desire to secure by Letters Patent of the United States is:

1. Game apparatus, comprising a game board, ball drivers of Y-shape in formation adapted to be moved over and partially rotated on said board, goal keepers of V-shape in formation adapted to be partially rotated on the board, and means for actuating said drivers and goal keepers.

2. Game apparatus comprising a game board provided with parallel guides, ball drivers movable along said guides, and an operating device connected to each driver for imparting both rotary and reciprocatory movements thereto. 65

3. Game apparatus comprising a game board, ball drivers movable thereover, and an operating device connected to each driver for alternatively rotating it or shifting it 70 forward or backward.

4. Game apparatus comprising a game board, Y-shaped ball drivers movable thereover, and means for operating said drivers.

5. Game apparatus comprising a game 75 board, Y-shaped drivers movable thereover, and means for imparting both reciprocatory and rotary movements to said drivers.

6. Game apparatus comprising a game board, Y-shaped drivers movable thereover, 80 and an operating device individual to each driver for imparting both reciprocatory and rotary movements thereto.

7. Game apparatus comprising a game board, ball drivers movable thereover, and 85 an operating device individual to each driver for imparting both backward and forward and rotary movements thereto, each operating device comprising a pair of parallel-motion rods connected at one end to 90 the driver and a handle connected to the other end of said rods.

8. Game apparatus comprising a game board provided with guides, ball drivers adapted to be moved along and rotated in 95 said guides, a pair of relatively-displaceable rods connected at one end to each driver, and an operating member connected to the other end of each pair of rods.

9. Game apparatus comprising a game 100 board provided with slots, ball drivers adapted to be moved forward and backward along and rotated in said slots, and a single operating device individual to each driver for imparting both movements thereto. 105

10. Game apparatus comprising a game board provided with a pair of oppositely-located goals, ball drivers adapted to be moved over and rotated on said board, goal keepers adapted to be rotated on said board, 110 and individual actuating means for said drivers and said goal keepers.

In testimony whereof I have signed this specification in the presence of two subscribing witnesses.

REGINALD ARTHUR KING.
